(57) **CLAIM**

The ornamental design for an electrical connector, as shown and described.

DESCRIPTION

The present application is related by subject matter to U.S. design patent application Ser. No. 29/384,319 filed Jan. 28, 2011; and U.S. design patent application Ser. No. 29/384,320 filed Jan. 28, 2011.

FIG. 1 is a top, right, front perspective view of an electrical connector according to my design;

FIG. 2 is a bottom, left, rear perspective view thereof;

FIG. 3 is a top plan view thereof;

FIG. 4 is a front elevation view thereof;

FIG. 5 is a bottom plan view thereof;

FIG. 6 is a rear elevation view thereof

FIG. 7 is a left side elevation view thereof; and,

FIG. 8 is a right side elevation view thereof.

The broken line portion of the figure drawings is included for the purpose of illustrating environment and forms no part of the claimed design.
